UNITED STATES PATENT OFFICE.

SIDNEY O. BIGNEY, OF PROVIDENCE, RHODE ISLAND.

DESIGN FOR A VEST FOB-CHAIN.

SPECIFICATION forming part of Design No. 32,246, dated February 20, 1900.

Application filed October 12, 1899. Serial No. 733,441. Term of patent 3½ years.

To all whom it may concern:

Be it known that I, SIDNEY O. BIGNEY, a citizen of the United States, residing at Providence, in the county of Providence and State of Rhode Island, have invented and produced a new and original Design for Vest Fob-Chains; and I do hereby declare that the following is a full, clear, and exact description thereof, reference being had to the accompanying drawing, which forms a part of this specification.

My invention relates to a design for vest fob-chains; and the essential features of my invention consist in a vertical fob-chain having a chain extension upon its upper end and a chain extending at an angle to the fob-chain and connected to one of the links of the vertical chain, as will be more fully described hereinafter.

The accompanying drawing represents a fob-chain embodying my invention.

I take a vertical fob-chain, which is shown as composed of three strands of chain connected at their ends by cross-bars. To the upper end of this fob-chain is connected a short vertical chain, and fastened to one of the links of this chain and extending at an angle to the fob and chain is a guard-chain having a cross-bar attached to its outer end. 25

Having thus described my invention, I claim— 30

The design for a vest fob-chain, substantially as shown and described.

In testimony whereof I have hereunto set my hand this 6th day of October, A. D. 1899. 35

SIDNEY O. BIGNEY.

In presence of—

BENJ. ARNOLD,
M. E. CLEVELAND.
